UNITED STATES PATENT OFFICE.

ELIZABETH KOLLER, OF BLOOMVILLE, OHIO.

DESIGN FOR A COMBINED SHIELD AND CUTTER.

SPECIFICATION forming part of Design No. 28,312, dated February 22, 1898.

Application filed December 20, 1897. Serial No. 662,756. Term of patent 14 years.

To all whom it may concern:

Be it known that I, ELIZABETH KOLLER, a citizen of the United States, and a resident of Bloomville, in the county of Seneca and State of Ohio, have invented and produced a new and useful Design for a Combined Fruit-Jar Shield and Doughnut-Cutter; and I do hereby declare that the following is a full, clear, and exact description of the invention, which will enable others skilled in the art to which it appertains to make and use the same, reference being had to the accompanying drawings, which form a part of this specification.

My invention relates to a new and novel combined shield for use in filling fruit-jars and a doughnut-cutter which shall be very useful as well as present an ornamental appearance; and the leading features of my design consist in the circular top plate or ring provided with a downwardly-depending cylindrical flange, an inner concentric tube, and the funnel connected with the upper side of said ring.

In the accompanying drawings, Figure 1 is an elevation of a combined fruit-jar shield and doughnut-cutter made in accordance with my design. Fig. 2 is a central longitudinal section of the same.

In the said drawings the reference-numeral 1 designates a circular top plate or ring formed or provided with a downwardly-depending cylindrical flange 2, an inner tube 3, concentric therewith, and a funnel 4, connected with the upper side of said ring.

What I claim is—

The design for a combined fruit-jar shield and doughnut-cutter, substantially as shown and described.

In testimony that I claim the foregoing as my own I have hereunto affixed my signature in presence of two witnesses.

ELIZABETH KOLLER.
